(57) **CLAIM**

The ornamental design for a surgical retractor as shown and described.

DESCRIPTION

FIG. 1 is a rear, right-side perspective view of a surgical retractor showing my design;

FIG. 2 is a front elevation view of the surgical retractor of FIG. 1;

FIG. 3 is a rear elevation view of the surgical retractor of FIG. 1;

FIG. 4 is a left-side elevation view of the surgical retractor of FIG. 1;

FIG. 5 is a right-side elevation view of the surgical retractor of FIG. 1;

FIG. 6 is a top plan view of the surgical retractor of FIG. 1;

FIG. 7 is a bottom plan view of the surgical retractor of FIG. 1;

FIG. 8 is a section view of the surgical retractor of FIG. 1, taken in the direction of plane 8-8 of FIG. 4;

FIG. 9 is a section view of the surgical retractor of FIG. 1, taken in the direction of plane 9-9 of FIG. 4;

FIG. 10 is a section view of the surgical retractor of FIG. 1, taken in the direction of plane 10-10 of FIG. 4;

FIG. 11 is a section view of the surgical retractor of FIG. 1, taken in the direction of plane 11-11 of FIG. 4;

FIG. 12 is a section view of the surgical retractor of FIG. 1, taken in the direction of plane 12-12 of FIG. 4;

FIG. 13 is a section view of the surgical retractor of FIG. 1, taken in the direction of plane 13-13 of FIG. 4; and,

FIG. 14 is a section view of the surgical retractor of FIG. 1, taken in the direction of plane 14-14 of FIG. 4.

1 Claim, 7 Drawing Sheets
